GLASS GRINDING MACHINE.
APPLICATION FILED APR. 11, 1914.

Patented July 14, 1914.

2 SHEETS-SHEET 2.

UNITED STATES PATENT OFFICE.

ERNEST STALZER, OF NEW YORK, N. Y.

GLASS-GRINDING MACHINE.

1,103,093.

Specification of Letters Patent. Patented July 14, 1914.

Application filed April 11, 1914. Serial No. 831,119.

To all whom it may concern:

Be it known that I, ERNEST STALZER, a subject of the Emperor of Austria-Hungary, residing at New York city, borough of Brooklyn, county of Kings, State of New York, have invented certain new and useful Improvements in Glass-Grinding Machines, of which the following is a full, clear, and exact description.

10 This invention relates to an improvement in glass-grinding machines, the object being to provide a grinding machine which is more particularly adapted to grind or bevel the ends of glass rods or tubes, special 15 clutching means being provided and special means to grind bevels of different angles being also provided.

I will now proceed to describe my invention in detail, the essential features of 20 which will be summarized in the appended claims, reference being had to the accompanying drawing, forming part hereof, wherein:

Figure 1 is a longitudinal sectional view 25 of my improved grinding machine; Fig. 2 is a plan view thereof; Fig. 3 is an enlarged cross-section, the section being taken on a line 3—3 in Fig. 1; Fig. 4 is an enlarged sectional detail view of a portion of the 30 clutch-jaw holder and a clutch-jaw; Fig. 5 is a side elevation of the machine; and Fig. 6 is an enlarged end view of the clutch-jaw holder and supporting head.

My improved glass grinding machine consists of a frame 1 pivoted as at 2 to a plate 3 slidably mounted on guides 4^a carried by a suitable standard. The frame 1 is provided with a hollow rotatable shaft or spindle 5 in which the article indicated by 40 6 (in this instance a glass rod) is placed. To hold the rod in place, I provide a clutch mechanism consisting of a holder 7, secured to the shaft 5, and rotatably supported in a head 7^a on the frame 1, the said holder being 45 provided with a plurality of slidably mounted clutch-jaws 8 faced on the inner ends with leather or other highly frictional substance indicated by 9, the said jaws being adapted to aline with the bore of the shaft 5. The clutch-jaws 8 are held in guide- 50 ways 10 in the holder 7, and are adapted to move freely in said guide-ways. Each jaw 8 is provided with a recess 10^a to receive the rounded end 11 of a lever 12. The levers 55 12 are pivoted as at 13 to a fulcrum head 14 integral with the holder 7. To actuate

the levers 12, which in turn actuate the clutch-jaws 8, I provide a cone 15 slidably mounted on the shaft 5. To actuate the cone, I provide a forked lever 16 pivoted as at 17 to the frame 1. The forked lever is actuated by a foot pedal 16^a, which actuates the rod 18 secured to the short arm 17^a of the forked lever 16. The shaft 5 can be rotated by any suitable mechanism. In combination with the clutch mechanism and rotatable shaft 5, I employ a rotatable grinding stone or element indicated by 20, which acts to bevel and grind the end of the glass rod 6 at the outer end 21.

To operate the device, I place the rod in the shaft 5, then depress the foot pedal, which actuates the forked lever 16 to slide the cone 15 to the left, which action raises the arms 22 of the levers 12, causing the short arms 23 of said levers to force the clutch-jaws 8 against the rod 6, which protrudes beyond the end of the shaft 5 as shown in Fig. 4, and grip the same. I then turn the frame 1 upon its pivot until the required angle is obtained, after which I tighten the binding screw 24 and lock the frame at the required angle. I then start the device for rotating the shaft 5, after which I slide the frame 1 toward the rotating grinding element 20 by means of the rack 25 on the plate 3 and intermeshing pinion 26 carried by the rotatable shaft 27. The rod is forced against the grinding element until the required bevel is obtained. The rod can be removed after grinding by releasing the foot-pedal, causing the spring 25^a to move the cone toward the right, at which time the springs 26^a will cause the jaws 8 to open and release the rod 6, which can be withdrawn for the purpose of grinding the other end thereof, or for complete removal. To grind the end of the rod, the said rod is placed in the shaft 5 in such position as to cause the end to aline with the surface 28 of the grinding stone. By means of the rack 25 and rotatable pinion 26 the plate 3 is moved inwardly causing the end of the rod to contact with the stone. To limit the inward movement of the plate, I provide an adjustable stop 29 actuated by a threaded rotatable spindle 30. The plate 3 will strike the stop when it has been moved the required distance. For beveling, the rod 6 is drawn out of the shaft the required distance. The frame 1 is then angularly adjusted and caused to move inwardly by

the aforesaid rack and pinion. To limit the inward movement of the plate, for grinding purposes, I provide an auxiliary stop consisting of a lever 31 having a rounded end 32. The lever is moved to cause the rounded end to be positioned ahead of the plate 3, hence when the said plate has moved inwardly the required distance the stop or end 32 will strike the adjustable stop 29.

Having now described my invention, what I claim and desire to secure by Letters Patent, is:

1. A glass grinding and beveling machine consisting of a standard, a slidable plate carried thereby, a frame pivotally supported by said plate, means to slide said plate, an adjustable stop carried by said standard adapted to limit the inward movement of said plate, a head carried by said pivoted frame, a rotary carrier located therein, a plurality of clutch jaws carried by said carrier adapted to grip a glass rod, means to actuate said jaws and a grinding element.

2. In a glass grinding machine, the combination of a slidable plate with a frame pivoted thereon, means for sliding said plate, an adjustable stop for limiting the inward movement of said plate, clutch jaws adapted to grip a glass rod, means for rotating said jaws and rod, a grinding element held in position for contact with said rod and means for sliding said plate.

3. In a glass grinding machine, the combination of a stationary grinding element with a tubular shaft adapted to contain a glass rod and arranged to present it to the said grinding element, means carried by said shaft for clutching said rod, means for rotating said shaft, means for varying the inclination of said shaft with respect to said grinding element, means for feeding said shaft toward said grinding element and an adjustable stop for limiting the movement of said shaft.

4. In a glass grinding machine, the combination of a stationary grinding element with a tubular shaft adapted to contain a glass rod and arranged to present it to said grinding element, clutching jaws for said rod turning with said shaft, means for closing said jaws on said rod, means for rotating said shaft and jaws, means for varying the angular position of said rod with respect to said grinding element and means for moving said shaft and rod toward and from said element.

5. A glass grinding and beveling machine consisting of a standard, a slidable plate carried thereby, a frame pivotally supported

by said plate, means to slide said plate, an adjustable stop carried by said standard adapted to limit the inward movement of said plate, an auxiliary stop for said plate also carried by said standard, a head carried by said pivotal frame, a rotary carrier located therein, a plurality of clutch jaws carried by said carrier adapted to grip a glass rod, means to actuate said jaws, and a grinding element.

6. A glass grinding and beveling machine consisting of a standard, a slidable plate carried thereby, a frame pivotally supported by said plate, means to slide said plate, an adjustable stop carried by said standard adapted to limit the inward movement of said plate, an auxiliary stop for said plate also carried by said standard, a hollow shaft carried by said frame, a carrier secured to said shaft, a plurality of clutch jaws carried by said carrier, a lever for each jaw, a fulcrum for said levers integral with said carrier, a head carried by said frame rotatably supporting said carrier, a cone slidably mounted on said hollow shaft adapted to actuate said levers, a foot pedal to actuate said cone, an adjustable stop to limit the inward movement of said slidable plate, means to actuate said stop, and a grinding element.

7. A glass grinding and beveling machine consisting of a standard, a slidable plate carried thereby, a frame pivotally supported by said plate, means to slide said plate, an adjustable stop carried by said standard adapted to limit the inward movement of said plate, an auxiliary stop for said plate, also carried by said standard, a hollow shaft carried by said frame, a carrier secured to said shaft, a plurality of clutch jaws carried by said carrier, a lever for each jaw, a fulcrum for said levers integral with said carrier, a head carried by said frame, rotatably supporting said carrier, a cone slidably mounted on said hollow shaft adapted to actuate said levers, a foot pedal to actuate said cone, an adjustable stop to limit the inward movement by said slidable plate, a threaded spindle to actuate said stop, an auxiliary stop for said slidable plate consisting of a lever pivoted to said plate provided with a head adapted to be moved to a position between said adjustable stop and the adjacent end of said plate, and a grinding element.

Signed at New York city, N. Y., this 7th day of April, 1914.

ERNEST STALZER.
